D. E. EDWARDS

INSECT EXCLUDER

Filed Sept. 24, 1924

UNITED STATES PATENT OFFICE.

DARSIE E. EDWARDS, OF CLINTON, MISSOURI.

INSECT EXCLUDER.

Application filed September 24, 1924. Serial No. 739,596.

To all whom it may concern:

Be it known that I, DARSIE E. EDWARDS, a citizen of the United States, residing at Clinton, in the county of Henry and State 5 of Missouri, have invented certain new and useful Improvements in Insect Excluders; and I do declare the following to be a full, clear, and exact description of the invention, such as will enable others skilled in the 10 art to which it appertains to make and use the same, reference being had to the accompanying drawings, and to the figures of reference marked thereon, which form a part of this specification.

15 This invention relates to an improved device for excluding insects from habitations and particularly to a novel device for preventing the passage of flies through the doorway of houses, equipped with the invention. Experience has taught that flies congregate or swarm about the upper part 20 of the doorway and they are usually found at the upper edge of the door and along the upper portion of the vertical edge of the door, usually above the height of a normal person. When the door is opened, the flies are disturbed and enter the doorway over the top of the door and pass the upper portion of the vertical edge of the 25 door, then when the door is closed they are trapped within the room. They seldom enter from the bottom portion of the doorway because their passage would naturally be obstructed by the person entering or leaving 30 the building through the doorway opening.

35 I have provided a novel means for preventing the liability of the flies finding access to the building through the space between the upper end of the door and the door frame or along the upper vertical edge of the door.

The invention contemplates the provision 40 of a horizontal wall or canopy in close proximity to, but slightly above the upper edge of the door. The top of the canopy or wall is in a plane parallel to that described by the upper end of the door when it is swung to and fro and I prefer to attach to the upper end of the door a flexible 45 wiper or strip which will maintain a close relation between the canopy and the door during the swinging movement of the door.

50 My invention further contemplates a canopy which is interchangeable for doors having right hand hinges or left hand hinges and the invention consists in certain novel

parts and combinations of parts, all of which will be specifically described herein-after, reference being had to the accompanying drawings in which—

60 Fig. 1 is a perspective view of a canopy constructed in accordance with my invention.

Fig. 2 is a fragmentary perspective view of one corner of a door with the wiper 65 attached.

Fig. 3 is a perspective view of the canopy viewed from the top, parts being broken away.

Fig. 4 is a perspective view of part of 70 the canopy frame, and

Fig. 5 is a similar view of another part of the canopy frame.

The door frame 1 is of usual construction and its opening may be closed by a 75 door 2 hinged in the usual way as by hinges, like the one indicated at 3 in Fig. 1. The door 2 is illustrated as a screen door. Along the upper edge is a flexible strip or wiper 4 and extending from the upper edge a 80 suitable distance downwardly is a wiper 5 located along the free longitudinal edge 6 of the door.

Fastened to the door frame above the door is a canopy. The canopy is of novel 85 construction. It is illustrated as consisting of straight bars 7 and 8 arranged at angles of about 90° and connected by a bolt 9 which extends through an angular bracket 10 fastened to the door frame by a 90 screw 11 or other suitable device. The bar 8 is offset as at 12 to provide a seat for the bar 7, see Fig. 1. The bars 7 and 8 are connected at their outer ends by an arcuate bar 13 which is shown as a quadrant, that is 95 the bar is equivalent to one-fourth of a circle and it is received in offset portions or seats 14 and 15 on the bars 7 and 8.

The ends of the bars extend downwardly to provide stiffening fingers 16 and 17 to 100 maintain the canopy fabric or cloth in proper position. The arcuate bar 13 is fastened to the arms 7 and 8 by bolts 18 and 18'. The bolt 18 is illustrated as passing through the members 13 and 7 and through 105 a bracket 19 which is fastened to the door frame by a screw or other suitable device 20. The bar 7 rests against the door frame. The bar 8 extends outwardly from the door frame but it is braced by a brace rod 21, one 110 end of which may be fastened to the door frame 1, the other end being threaded and

extending through a bracket 22 on the bar 8.

The threaded end 23 of the brace rod 21 receives a nut 24 by means of which an adjustment may be made for taking up slack in the canopy frame. The bar 7 is provided with an opening 25 through which the bolt 26 for the bracket 22 may be inserted when it is desired to use the canopy for a door swinging in the direction opposite to the one illustrated in Fig. 1. In that event the bracket 19 will be removed from the bolt 18 and located on the bolt 18'. The bracket 22 will be swung over to the bar 7 and fastened in the opening 25. The bracket 11 may then be swung around at an angle of 90° to its present position whereupon the canopy frame can be erected on a door swung in a direction opposite to that shown in Fig. 1.

The canopy fabric 27 has a skirt 28 which extends along the arcuate edge 29 of the fabric portion 27. The bars 7 and 8 are inserted in hems 30 and 31 and the arcuate bar 13 is inserted in the hem 32. The skirt is stiffened by an arcuate stiffening bar 33. The top of the canopy fabric is positioned in substantially the location shown in Fig. 1 so

that when the door is opened, the wipers 4 and 5 will remove the flies from the under side of the top of the canopy and from the skirt. The door will not open beyond the edge described by the bar 8, so liability of flies entering the room from the upper part of the door opening will be entirely eliminated.

What I claim and desire to secure by Letters-Patent is:—

1. An insect excluder for doorways comprising a fabric supporting frame, a bracket adjustably engaging the frame, and means on the bracket for attachment to the door frame.

2. An insect excluder for doorways comprising a horizontally disposed bracket arm, means for securing the bracket arm to the door frame, an arcuate arm adjustably carried by the free end of the first named arm, a fabric having one edge supported by the arcuate arm, and means for securing the opposite edge of the fabric to the doorway frame.

In testimony whereof I affix my signature.

DARSIE E. EDWARDS.
